C. DYER, JR., AND ELLIS DRAKE, OF STOUGHTON, MASSACHUSETTS.

Letters Patent No. 67,422, dated August 6, 1867.

IMPROVED BOOT AND SHOE-HEELS.

The Schedule referred to in these Letters Patent and making part of the same.

TO ALL WHOM IT MAY CONCERN:

Be it known that we, C. DYER, Jr., and ELLIS DRAKE, of Stoughton, Norfolk county, Massachusetts, have invented a new and useful improvement in Boots and Shoes; and we do hereby declare that the following is a full, clear, and exact description thereof, which will enable others skilled in the art to make and use the same, reference being had to the accompanying drawings forming part of this specification.

The present invention consists in providing the heel of a boot or shoe with a series of India-rubber or other elastic studs, which are first secured to a metallic plate, and then by such plate fastened to the under or the ordinary treading surface of the heel. This invention also consists in the use of a metallic shank piece that is applied and secured to the boot or shoe-sole in a novel manner, as will be hereinafter particularly described. In the accompanying plate of drawings our improvement in boots and shoes is illustrated.

Figure 1 is a plan view of the treading surface of a boot or shoe heel made according to the present invention, and

Figure 2 a central longitudinal section.

Similar letters of reference indicate corresponding parts.

A, in the drawings, represents the boot or shoe-heel, to the treading surface B of which a plate, C, is secured by means of a centre-screw or bolt, D, screwing by its inner end into the screw-nut E, fixed in position upon the inside of the heel. This plate C is provided with a series of India-rubber or other elastic studs, F, which are headed at one end, G, and by such headed ends held in the openings H, made in the plate C to receive them. I, the metallic shank piece, which forms a continuation of the screw-nut E for the bolt D.

Among the many advantages secured by our improvement in boot and shoe-heels may be here mentioned that it is simple, strong, cheap, practical, and durable; that it imparts a safe and sure footing or tread to the boot or shoe.

We claim as new, and desire to secure by Letters Patent—

The elastic studs F in the perforated plate C, clamped by their heads G between such plate and the treading surface B of the boot-heel by means of the centre-screw D fitting into the nut E upon the shank I, all constructed and arranged as herein set forth for the purpose specified.

The above specification of our invention signed by us this 17th day of December, 1866.

C. DYER, JR.,
ELLIS DRAKE.
